GRINDING WHEEL TRUING MECHANISM

William B. Seidel, Cincinnati, Ohio, assignor to The Cincinnati Milling Machine Co., Cincinnati, Ohio, a corporation of Ohio

Filed Nov. 8, 1960, Ser. No. 68,070

10 Claims. (Cl. 125—11)

This invention relates to a grinding wheel truing mechanism adapted for use in a precision grinding machine.

In the manufacture of angular contact annular ball bearings, it is necessary to grind a workpiece profile which includes both an arcuate portion and an adjacent straight portion. It is a common practice not to make the straight portion exactly tangent to the arcuate portion, but rather to leave a slight corner condition between the two surfaces which will hold the balls in the arcuate ball track. The arcuate portion must be ground to a depth slightly greater than that to which the straight profile portion is ground. Each of the two surfaces is generally ground in a separate operation, the arcuate track being ground first and the straight portion being ground in a subsequent operation. It is a better practice to grind both the arcuate ball track and the flat land in one operation.

In grinding both profile surfaces in one operation, an accurate grinding wheel profile must be generated and maintained. This requires an accurate truing mechanism which will create a peripheral contour, the parts of which will not change relative to one another in succeeding truing operations. With a wheel profile having a slight corner between straight and arcuate portions thereof, cam guidance at the corner is difficult. Moreover, the use of a cam restricts the flexibility of use of the machine since a different cam is required for each contour.

It is therefore an object of this invention to provide a truing mechanism whereby an arcuate portion and adjacent straight portion may be trued on a grinding wheel periphery by a single truing tool in a single truing operation without cam guidance.

It is a further object to provide a mechanism whereby an arcuate profile portion and an intersecting adjacent straight profile portion may be trued on the periphery of a grinding wheel.

It is another object of this invention to provide a truing mechanism whereby the path of the truing tool may be altered to true a variety of grinding wheel profiles having straight and arcuate profile portions.

Still another object is to provide a mechanism for truing a straight profile portion and an arcuate profile portion in one continuous movement of the truing tool which is simply and inexpensively constructed yet which is accurate through repeated operations.

Other objects and advantages of the present invention should be readily apparent by reference to the following specification, considered in conjunction with the accompanying drawings forming a part thereof, and it is to be understood that any modifications may be made in the exact structural details there shown and described, within the scope of the appended claims, without departing from or exceeding the spirit of the invention.

A truing mechanism constructed in accordance with the preferred form of this invention utilizes a single point truing tool mounted in a truing slide member. The truing slide member is received for reciprocal movement in a truing yoke which is pivotal relative to the grinding wheel. A rotary driving member develops a torque which is divided by the mechanism to produce movement of the truing slide in the yoke and pivotal movement of the yoke, the yoke remaining stationary while the slide is moved therein. The relative movements of the slide and yoke are adjustable to produce movement of the truing tool through a path by which an arcuate profile portion inter-

2

sected by a straight profile portion may be trued as well as a profile in which the straight portion is tangent to the arcuate portion. The mechanism is accurate and the same profile may be repeatedly trued.

5 The construction and operation of the truing mechanism are described in the following detailed description with reference to the attached drawings wherein:

FIG. 1 is an elevational view of the truing mechanism.

FIG. 2 is a sectional view of FIG. 1 on line 2—2.

10 FIG. 3 is a sectional view of FIG. 2 on line 3—3.

FIG. 4 is a sectional view showing the details of the drive input mechanism.

FIG. 5 is a sectional view of FIG. 4 on line 5—5.

15 FIG. 6 is a schematically represented hydraulic circuit to operate the truing attachment.

FIG. 7 is an electrical control circuit for operation of the hydraulic circuit of FIG. 6.

FIG. 8 is a sectional view of FIG. 3 on line 8—8.

20 FIG. 9 is a partial section of a grinding wheel showing the profile of the grinding periphery.

As shown in FIG. 1, the truing mechanism is located behind the grinding wheel 10 which is rotatably supported in a grinding machine wheelhead 11. The truing mechanism is supported by a truing carriage 12 which is received by a slide housing 14 that is fixed in the wheelhead 11 and forms a part thereof. The grinding wheel 10 rotates about an axis which is fixed relative to the slide housing 14 of the wheelhead. The truing carriage 12 is movable toward and away from the grinding wheel 10 by selected rotation of a compensation screw 16 which is axially fixed relative to the slide housing 14 and threadedly engaged with the truing carriage. The compensation screw 16 is utilized to move the truing carriage 12 relative to the slide housing 14 toward the grinding wheel 10 to maintain the truing mechanism in a position to perform a truing operation as the grinding wheel 10 is reduced in diameter through use.

Fixed on the end of the truing carriage 12 and forming a part thereof is a bracket 18 in which a yoke 20 is pivotally received. The yoke 20 is held in the bracket 18 by pins 22, 24 fixed therein and extending from the yoke into the bracket where they are in pivotal contact with balls 26, 28 respectively. The balls 26, 28 are held in place in the bracket 18 by pin seats 30, 32 respectively, fixed in the bracket. Also contained in the bracket 18 above the yoke 20 is a gear mechanism 34 by which a truing tool 42 is moved during a truing operation. The mechanism 34 is actuated by a pair of pistons 36, 38 (FIG. 6) which are received in a cylinder block 40 that is fixed on the rear of the bracket 18.

The single point truing tool 42 is carried in the yoke 20 for truing the grinding wheel 10 when moved across the peripheral cutting surface thereof. As shown in FIGS. 2 and 3, the truing tool 42 is received in a truing slide member 44 which is received in the yoke 20 on antifriction balls 46. The anti-friction balls 46 are received in ball tracks 48, 50 in the yoke 20 and held in spaced relationship to one another by cage members 52, 54. The truing tool 42 is adjustable toward and away from the grinding wheel 10 by rotation of a screw 56 which is received through a sleeve 58 that extends through a slot 60 at the rear of the yoke 20. The truing tool 42 is held in a fixed angular position in the truing slide 44 since it has a longitudinal slot 62 (see FIG. 8) on one side engaged by a key pin 64 fixed in the truing slide. When the truing tool 42 is axially positioned to true a particular radius, with the point of truing tool 42 a predetermined distance from the axis defined by the center of pivot balls 26, 28, a locking screw 66 is tightened down to rigidly fix the tool in the truing slide 44.

By moving the truing slide 44 in the yoke 20 while holding the yoke stationary, a straight profile portion may be

trued on the grinding wheel 10. By stopping the movement of the truing slide 44 in the yoke 20 and then by swinging the yoke, the point of the truing tool 42 will move in an arcuate path for truing an arcuate profile portion on the peripheral surface of the grinding wheel 10.

The gear mechanism 34 is shown in detail in FIG. 4. Limited rotary motion is introduced to the actuating mechanism 34 from the pair of reciprocating pistons 36, 38 in the cylinder block 40 (FIG. 6). Connected to each of the pistons 36, 38 is a drive chain 68. The chain 68 is pinned at its center 70 to a rotatable sleeve 72. The sleeve 72 is received in annular bearings 74, 76 which are received in a retainer member 77 fixed in the bracket 18. The sleeve is rotatable around the pin 22, ball 26, and pin seat 30 as the chain 68 is moved. On the lower end of the sleeve 72 is a gear 78 which is fixed for rotation therewith by a key 80. A nut 82 holds the gear 78 on the sleeve 72. In mesh with the gear 78 is a sector gear 84 which is fixed to the upper end of a shaft 86 which extends into the yoke 20, as shown in FIG. 1, where it is journaled for rotation. As shown in FIG. 3, a pinion gear 88 is fixed on the lower end of the shaft 86. The pinion 88 is engaged with a rack 90 which is machined on the rear of the truing slide 44.

By the described mechanism, reciprocal motion of the pistons 36, 38 (FIG. 6), to which the chain 68 is attached at each end, is converted into rotary motion at the sleeve 72 (FIG. 4). The rotary motion of the sleeve 72 produces a torque which is transmitted from the gear 78 through the sector gear 84 to the shaft 86. The shaft 86, pinion 88, and rack 90 converts the torque into motion of the truing slide. To allow the truing slide 44 to be moved by the pinion 88, the yoke 20 must offer more resistance to movement than the slide 44 or otherwise the yoke would tend to be swung by the movement of the gear 78. An annular drag seal 92 is received in the bracket 18 and engaged with an annular surface 94 on the top of the yoke 20. The drag seal 92 in addition to keeping grinding dirt out of the gear mechanism, creates a resistance to movement of the yoke which, in combination with anti-friction balls 46, renders the truing slide 44 more freely movable than the yoke. Consequently rotary motion of the shaft 86 in the yoke 20 will occur and the truing slide 44 will move transversely in the yoke.

If the movement of the truing slide 44 in the yoke 20 is stopped before the rotary input of sleeve 72 is exhausted, the remaining torque produced at the sector gear 84 may be utilized to swing the yoke in the bracket 18. Therefore a pair of stop members 98, 100 (FIG. 2) are received in one side of the yoke 20 and a third stop member 102 (FIG. 8) is received in the same side of the yoke but extends through the truing slide 44 to the opposite side where it is adapted to engage the bottom of a counter-bored portion 104 thereof. (As shown in FIG. 2, stop 102 extends from the side of the yoke 20 and is covered by a guard member 96 which is normally received over the adjusting knob 102a of the stop during machine operation.) The stop 98 (FIG. 2) is a fixed stop and limits the extreme movement of the slide 44 at the right side of the yoke 20. The stop 100 is an adjustable stop which may be used in place of the fixed stop 98 to restrict the extreme movement of the slide 44 to the right in the yoke 20 but to a selected point to the left of the fixed stop 98. As shown in FIG. 2 the truing slide 44 is in its extreme right position. The left side stop 102 (FIG. 8) is adjustable relative to the yoke 20 in which it is threadedly received. Assuming that the stop 102 is at its extreme left adjustment, the dimension 106 represents the allowable movement of the truing slide 44 in the yoke 20, or the length of the straight path which the truing tool 42

70

75

By the construction described, assume that the sleeve 72 (FIG. 4) may be rotated through a reciprocal rotary movement of 180 degrees by operation of the pistons 36, 38 (FIG. 6). Of this motion, 90 degrees in one direc-

tion is necessary to move the truing slide 44 (FIG. 2) from engagement with the fixed stop 98 through a distance 106 to engagement with the left stop 102. When the stop 102 is engaged by the truing slide 44 and the sleeve 72 (FIG. 4) continues to rotate in the same direction, the balance of the rotary movement, 90 degrees, is transferred to the yoke 20 to swing it through an arcuate path. The engagement of the stop 102 by the truing slide 44 fixes the truing slide in the yoke 20 and the force created by the continued rotary movement of the sleeve 72 in the same direction is transmitted through the stop 102 to the yoke 20. The force produced thereby tending to swing the yoke 20 is greater than the resistance to movement of the yoke created by the drag seal 92. The yoke 20 then becomes more freely movable than the truing slide 44 during continued rotation of the sleeve 72 through the second 90 degrees.

By the combination of the movement of the truing slide 44 in the yoke 20 and the subsequent pivotal movement of the yoke, the truing tool 42 is carried along a path having a straight portion and an arcuate portion. The point of the truing tool 42 then may be utilized to true a grinding wheel 10 having a profile contour which includes a straight portion and an arcuate portion. If the stop 102 (FIG. 8) is positioned such that the point of the truing tool 42 is swung about a radius which is equal to the perpendicular distance from the center of the radius to the straight portion of the path traced by the point, the straight portion of the path would be tangent to the arcuate portion of the path. The mechanism may then be used to true such a profile on the periphery of the grinding wheel 10. The point of tangency and the center C of the arcuate portion define a centerline of pivot CL, FIG. 9, used as a reference line for altering the relationship of the straight and arcuate portions of the path traced by the truing tool 42.

If the stop 102 (FIG. 8) is adjusted to terminate the movement of the truing slide 44 in the yoke 20 at a place where the point of the truing tool 42 (FIG. 3) is swung about a radius which is greater than the perpendicular distance from the center of the radius to the straight portion of the path, the straight portion of the path traced by the truing tool would intersect the arcuate portion of the path, that is, the straight portion would not be tangent to the arcuate portion. One form of this condition is shown in FIG. 9. The grinding wheel 10 has a straight profile portion 108 and an arcuate profile portion 110. The available straight movement of the truing tool is represented by dimension 112 and is equal to the dimension 106 in FIG. 8. If all available straight movement were used, the resulting form would be a straight portion tangent to an arcuate portion. The stop 102, however, is adjusted to the right (FIG. 8) to shorten the path of the truing slide by an amount equal to dimension 114 to offset the start of the arcuate path from the center line of pivot CL. When the straight movement of the truing slide 42 is stopped, the swing of the yoke 20 begins. The point of the truing tool 42 now traces an arcuate path the radius R of which is greater than the perpendicular distance 116 from the center C of the arcuate portion 110 to the straight portion of the path. Thus a stepped relation is created on the grinding wheel periphery, the step being represented by the dimension S, and the straight portion 108 intersects the arcuate portion 110. The offset dimension 114 may be expressed relative to the radius R and step S by the formula;

$$\text{offset} = \sqrt{R^2 - (R-S)^2}$$

Therefore, by calibrating the knob 102a (FIG. 8) on the stop 102, the truing mechanism may be conveniently adjusted to true a range of stepped forms on the grinding wheel.

In the specific embodiment described herein, the total straight movement is assumed to be such that at full movement of the truing slide 44, a straight surface tan-

gent to an arcuate surface is trued. By extending the slide movement beyond the dimension 106 (FIG. 8), the mechanism would true a straight surface which would intersect the arcuate surface but which would produce no step. In such a case the offset would be in the opposite direction from the centerline of pivot CL from the offset 114 shown in FIG. 9.

In truing the wheel form in FIG. 9, the truing tool 42 would move from position 118 through a straight path and succeeding arcuate path and stop at position 120. The truing tool must then be returned to its starting position 118. This is done by reversing the action of the pistons 36, 38 (FIG. 6). The sleeve 72 (FIG. 4) is then rotated through 180 degrees in the opposite direction. Initially, the truing slide 44 moves more freely since the shaft 86 is rotated in a direction tending to move the truing slide from engagement with stop 102 (FIG. 8) toward stop 98 (FIG. 2) and the drag seal 92 (FIG. 4) opposes movement of the yoke in the opposite direction. Therefore the truing slide 44 moves first in the yoke 20 and then the yoke finally swings to its starting position. In such a motion, the truing tool 42 would be moved away from the grinding wheel 10 (FIG. 9) and returned to its starting position 118 without contacting the grinding wheel. Truing contact then occurs only when the truing tool 42 moves from the start position 118 to the stop position 120.

To insure that the mechanism trues the same contour each time and that the spaced relationship of the arcuate portion and the straight portion of the periphery remains constant, the return swing of the yoke 20 to the starting position must end at the distance from the line CL each time. Therefore, a stop pin 122 (FIGS. 4, 5) is fixed in a cap 124 which is adjustable relative to the top of the bracket 18 and may be locked thereto by a draw-down bolt 125. The stop pin 122 extends through an arcuate clearance slot 128 in the bracket 18. The lower end of the stop pin 122 is adapted to engage a stop 130 fixed in an angle bracket 132 which is secured to the top of the yoke 20 and moves therewith. As shown in FIG. 5, the stop 130 is engaged with the stop pin 122 at the starting position 118. In a truing operation, the yoke 20 would move counterclockwise (as viewed in FIG. 5) and the stop 130 would move away from the stop pin 122 during the truing of the arcuate portion of the grinding wheel periphery. Upon the return swing of the yoke 20, the stop 130 would move back toward the stop pin 122 for engagement therewith. The use of the rigid stop 122 to terminate the return swing of the yoke 20 then places the yoke in the same starting position relative to line CL each time. Rigid stops 98, 100, 102 (FIGS. 2, 8) in the yoke 20 control the movement of the truing slide 44 and the result is repeated movement of the truing tool through an identical path.

An electrical control circuit is shown in FIG. 7 for operation of the truing hydraulic circuit shown in FIG. 6. In the starting condition, the piston 36 is in its forward position as shown and piston 38 is in the retracted position. Therefore, limit switch 1LS is operated and limit switch 2LS is in the released condition at the start of a truing cycle. (The trip point of both limit switches 1LS and 2LS may be adjusted in machine set up for a particular job.) With limit switch 1LS operated relay 5CR is energized. Switch SW1 is momentarily closed to start the truing cycle. During the moment that switch SW1 is closed, relay 1CR is energized through that switch and immediately relay 2CR is energized through contacts of relays 1CR and 5CR. Relay 2CR latches around the contacts of relay 5CR. Immediately, relay 3CR is energized through the contacts of relays 1CR, 2CR and 6CR (normally closed). Solenoid 1SOL is then energized through contacts of relay 3CR.

When solenoid 1SOL is energized the plunger of the reversing valve 134 shifts to the right from the position

shown in FIG. 6. The main fluid pressure line 136 is connected to the fluid line 138 which is connected in the cylinder block 40 to the left side of piston 36. Line 140 is connected through the valve 134 to return line 142. Piston 36 is forced to the right and the other piston 38 moves to the left as the chain 68 is moved. The sleeve 72 is rotated counterclockwise, and the truing tool movement begins. At this time limit switch 1LS is released and relay 5CR is deenergized. Switch SW1 may now be released since the latch circuit through contacts of relays 1CR and 5CR (normally closed) will hold relay 1CR energized.

After the pistons 36, 38 have completed their stroke, limit switch 2LS is operated by piston 36 have completed their stroke, limit switch 2LS is operated by piston 36 and as a result, relay 6CR is energized. When relay 6CR is energized relay 3CR is dropped to deenergize solenoid 1SOL. Relay 4CR is energized at this time through contacts of relays 5CR (normally closed), 1CR, and 6CR. Relay 4CR latches around contacts of relay 6CR. Solenoid 2SOL is now energized through contacts of relay 4CR and the plunger of valve 134 shifts to the left. Pressure line 136 is connected to fluid line 140, and return line 142 is connected to fluid line 138. The movement of the pistons 36, 38 is reversed to return the truing tool 42 to its starting position. Limit switch 2LS is released immediately as the reverse movement begins, dropping relay 6CR, and the limit switch 1LS is operated when the return is completed. Relay 5CR is energized when limit switch 1LS is operated. Relays 1CR and 4CR are dropped when relay 5CR is energized. When relay 1CR is deenergized, relay 2CR is also deenergized, and when relay 4CR is deenergized, solenoid 2SOL is deenergized.

The truing cycle is then completed, the truing tool having moved from its starting position to its finished position and then returned to the starting position. The length of the straight portion of the path of the truing tool 42 relative to the arcuate portion is determined by the length of movement of the slide 44 in the yoke 20 allowed by the setting of the stops 100, 102 relative to one another and to the fixed stop 98 and the amount of rotary movement of the sleeve 72 produced by the pistons 36, 38. The relationship of the straight portion to the arcuate portion is determined by the adjustment of the stop 102 relative to the centerline of pivot CL (FIG. 9).

If the stops 100, 102 (FIGS 2, 3) are adjusted to hold the truing slide 44 in a fixed position in the yoke, the entire rotary movement of the sleeve 72 (FIG. 4) would be transmitted to the yoke 20 which would rotate with the sleeve 72. The stop 122 (FIG. 5) would then be adjusted counterclockwise to allow a predetermined amount of arcuate movement of the yoke beyond the point shown. The full 180 degrees of movement of the sleeve 72 can be transmitted to move the yoke through a 180 degree swing for truing an arcuate profile across the entire grinding wheel width 109 (FIG. 9). The stop 122 would then be moved in the slot 128 to the end opposite that in which the stop is shown to allow for the full swing. As shown, the stop 122 is in a position which would allow for a swing of the yoke 20 of approximately 90 degrees with full movement of the truing slide 44 through the distance 106. The range of swing in the mechanism described can therefore be adjusted to any value between 90 and 180 degrees. If a radius of less than 180 degrees is desired on the profile with no straight portion, the stop 122 may be set in the appropriate position to provide an accurate starting position. The trip plungers of limit switches 1LS and 2LS (FIG. 6) would have to be adjusted to operate the control relays at the proper time since the pistons 36, 38 would not complete full travel in the cylinder block 40.

It is understood that the specific arcuate movements

referred to herein are for purposes of illustration only and are not intended to limit the scope of this invention.

What is claimed is:

1. In a grinding machine having a grinding wheel with a contoured profile thereon, a truing mechanism comprising in combination, a pivotally movable member mounted adjacent the grinding wheel, a slidably movable member received in said pivotally movable member for transverse movement therein, a truing tool received in said slidably movable member and extending therefrom toward said grinding wheel, means initially to render one of said movable members more freely movable than the other of said movable members, means to render the other of said movable members more freely movable than said one movable member after a predetermined movement of said one movable member, a drive member operatively connected to both of said movable members, one at a time in one direction in accordance with relative freedom of movement therebetween for truing a straight portion and an arcuate portion on the profile of said grinding wheel, and means to reversely move said drive member whereby said movable members move in the reverse direction one at a time to return said truing tool to a starting position.

2. In a grinding machine having a grinding wheel with a contoured profile thereon, a truing mechanism comprising in combination, a bracket mounted adjacent the grinding wheel, a pivotally movable member mounted on said bracket, a slidably movable member received in said pivotal member for transverse movement therein, means to render said slidable member more freely movable than said pivotal member, a truing tool received in said slidable member and extending therefrom toward said grinding wheel, a rotatable drive shaft journaled in the pivotal member and connected to said slidable member for movement thereof when rotated, a drive member connected to said drive shaft, means to rotate said drive member a predetermined amount initially to transmit rotation to said drive shaft in the pivotal member and move said slidable member therein, and means to stop movement of said slidable member in said pivotal member before said drive member has rotated said predetermined amount and to connect said drive shaft to said pivotal member for pivotal movement thereof, said truing tool thereby moved for truing a straight portion and an arcuate portion on the profile of said grinding wheel.

3. In a grinding machine having a grinding wheel with a contoured profile thereon, a truing mechanism comprising in combination, a bracket mounted adjacent the grinding wheel, a pivotally movable member mounted on said bracket, a slidably movable member received in said pivotal member for transverse movement therein, a truing tool received in said slidable member and extending therefrom toward said grinding wheel, means to render said slidable member more freely movable than said pivotal member, a rotatable drive shaft journaled in the pivotal member and connected to said slidable member for movement thereof when rotated, a drive member journaled in the bracket and connected to said drive shaft, means to rotate said drive member a fixed amount in one direction initially to transmit rotation to said drive shaft in the pivotal member and move said slidable member therein, means to stop movement of said slidable member in one direction in said pivotal member before said drive member has rotated said fixed amount and to connect said drive shaft to said pivotal member for pivotal movement thereof in one direction a predetermined amount, said truing tool thereby moved for truing a straight portion and an arcuate portion on the profile of said grinding wheel, means to effect rotation of said drive member said fixed amount in the other direction, and means to stop movement of said slidable member in the other direction in said pivotal member before said drive member has rotated said fixed amount and to connect said drive shaft to said pivotal member for piv-

8
otal movement thereof in the other direction a predetermined amount, said truing tool thereby returned to a starting position.

4. In a grinding machine having a grinding wheel with a contoured profile thereon, a truing mechanism comprising in combination, a bracket mounted adjacent the grinding wheel, a pivotally movable member received in said bracket on an axis, a slidably movable member received in said pivotally movable member for transverse movement therein, a truing tool received in said slidably movable member and extending therefrom toward said grinding wheel, means to render said slidably movable member more freely movable than said pivotally movable member, a rotatable drive shaft journaled in the pivotally movable member and spaced from said axis, said shaft connected to said slidably movable member for movement thereof when rotated, a drive member journaled in said bracket for rotation on said axis and connected to said drive shaft for rotation thereof, means to rotate said drive member a fixed amount one way and the other way, a pair of adjustable stop members received in said pivotally movable member for engaging said slidably movable member to stop movement thereof before said drive member rotates said fixed amount and to connect said drive shaft to said pivotally movable member for movement thereof, the adjustment of said stop members determining the relative amount of movement of said movable members effected by said fixed rotation of the drive member and the direction of said fixed rotation determining the direction of movement of said movable members, and means to advance said pivotally movable member toward said grinding wheel.

5. In a grinding machine having a grinding wheel with a grinding profile including an arcuate portion and a straight portion, a truing mechanism comprising in combination, a truing carriage received adjacent said grinding wheel, a yoke pivotally received in said carriage, a pair of transversely spaced stops in said yoke, a truing slide received in said yoke for movement between said stops, a truing tool fixed in said truing slide and extending therefrom toward said grinding wheel, a drive shaft journaled in said yoke and connected to said truing slide, said drive shaft operable, when a torque is applied thereto, to move said truing slide from one of said stops to the other of said stops and thereafter to pivot said yoke for movement of said truing tool to true said straight and arcuate portions, and means to apply a torque to said drive shaft.

6. In a grinding machine having a grinding wheel with a grinding profile including an arcuate portion and a straight portion, a truing mechanism comprising in combination, a truing carriage mounted adjacent said grinding wheel, a yoke pivotally received in said carriage on an axis, a pair of transversely spaced stops in said yoke, a truing slide received in said yoke for movement between said pair of stops, a truing tool fixed in said truing slide and extending therefrom toward said grinding wheel, a rotatable drive shaft journaled in said yoke and spaced from the pivot axis thereof, said drive shaft connected to said truing slide for movement thereof from one stop to the other stop of said pair of stops and thereafter for pivotal movement of said yoke when a torque is applied to said drive shaft, and a drive mechanism operable to produce a torque and including a drive member journaled in said carriage and rotatable about the pivot axis of said yoke, said mechanism connected to said drive shaft for transmission of said torque thereto to effect movement of said truing slide and said yoke for truing said straight and arcuate profile portions.

7. In a grinding machine having a grinding wheel with a grinding profile including a straight portion and an arcuate portion, a truing mechanism comprising in combination, a truing carriage received adjacent said grinding wheel, a yoke pivotally received in said carriage, a pair of transversely spaced stops in said yoke, a truing slide received in said yoke for movement between said stops, a truing

tool fixed in said truing slide and extending therefrom toward the grinding wheel, a rack fixed to said truing slide, a rotatable drive shaft journaled in said yoke, said shaft having a pinion fixed thereto and engaged with said rack, a drag member received in said carriage and engaged with said yoke, said drag member effective to impede movement of said yoke and to render said truing slide more freely movable than said yoke, means to apply a torque to said shaft to effect movement of said truing slide from one of said stops to the other of said stops and thereafter to pivot said yoke a predetermined amount in one direction, said truing tool thereby tracing a path for truing said straight portion and said arcuate portion, and means to reverse said torque to effect movement of said truing slide from the other of said stops to the one of said stops and thereafter to pivot said yoke said predetermined amount in the other direction.

8. In a grinding machine having a wheelhead and a grinding wheel rotatably received therein, said grinding wheel having a grinding profile including a straight portion and an arcuate portion, a truing mechanism comprising in combination, a truing carriage received in said wheelhead, a pivotally movable yoke received in said carriage on an axis, a positive stop in said carriage adapted to engage said yoke, a pair of transversely spaced stops in said yoke, a truing slide received in said yoke for movement between said pair of stops, a truing tool fixed in said truing slide and extending therefrom toward said grinding wheel, a rack fixed to said truing slide, a rotatable drive shaft journaled in said yoke, said drive shaft parallel to the pivotal axis of said yoke and spaced therefrom, a pinion fixed to said drive shaft and engaged with said rack, a drag member received in said bracket and engaged with said yoke to render said truing slide more freely movable than said yoke, means to apply a torque to said drive shaft to effect movement of said truing slide from one stop to the other stop of said pair of stops and thereafter to pivot said yoke a predetermined amount away from said positive stop, said truing tool thereby tracing a path for truing said straight portion and said arcuate portion, means to reverse said torque applied to said drive shaft to effect movement of said truing slide from the other stop to the one stop of said pair of stops and thereafter to pivot said yoke to engage said positive stop, and means to adjust the other stop of said pair of stops relative to the one stop of said pair of stops to change the path traced by said truing tool for altering the relation of said straight portion to said arcuate portion.

9. In a grinding machine having a wheelhead and a grinding wheel rotatably received therein, said grinding wheel having a grinding profile including a straight portion and an arcuate portion, a truing mechanism comprising in combination, a truing carriage received in said wheelhead for movement toward said grinding wheel, said carriage having a bracket extending therefrom, a pivotally movable yoke received in said bracket on a pivot axis, an adjustable positive stop received in said bracket and adapted to engage said yoke, a pair of adjustable transversely spaced stops in said yoke, a truing slide received in said yoke for movement between said pair of stops, a truing tool fixed in said truing slide and extending therefrom toward said grinding wheel, a rack fixed to said truing slide, a rotatable drive shaft journaled in said yoke, said drive shaft spaced from and parallel to the pivot axis of said

yoke, a pinion fixed to said drive shaft and engaged with said rack, a drag member received in said bracket and engaged with said yoke, said drag member effective to render said truing slide more freely movable than said yoke, means to apply a torque to said drive shaft in one direction to move said truing slide from one stop to the other stop of said pair of stops and thereafter to pivot said yoke away from said positive stop a predetermined amount for movement of said truing tool in said straight and arcuate paths to true said straight and arcuate portions of said grinding wheel profile, the relative adjustment of said pair of stops determining the relative length and relationship of said straight and arcuate paths and the positive stop determining the starting position from which said truing tool is moved, means to reverse said torque to rotate said drive shaft in the other direction and move said truing slide from the other stop to the one stop of said pair of stops and thereafter to pivot said yoke to engage said positive stop, and means to advance said carriage toward said grinding wheel for positioning said truing tool relative to the periphery of said grinding wheel.

10. In a grinding machine having a wheelhead and a grinding wheel rotatably received therein, said grinding wheel having a grinding profile including a straight portion and an arcuate portion, a truing mechanism comprising in combination, a truing carriage received in said wheelhead for movement toward said grinding wheel, said carriage having a bracket extending therefrom, a pivotally movable yoke received in said bracket on an axis, a positive stop received in said bracket and adapted to engage said yoke, a pair of transversely spaced stops in said yoke, a truing slide received in said yoke for movement between said pair of stops, a drag seal received in said bracket and engaged with said yoke, said seal effective to render said truing slide more freely movable than said yoke, a truing tool fixed in said truing slide and extending therefrom toward said grinding wheel, a rack fixed to said truing slide, a rotatable drive shaft journaled in said yoke and extending therefrom, said drive shaft parallel to and spaced from the pivot axis of said yoke, a gear fixed to said drive shaft outside said yoke, a pinion fixed to said drive shaft in said yoke and engaged with said rack, a drive member journaled in the bracket on the pivot axis of said yoke, said drive member having a drive gear fixed thereon and engaged with said gear, means to apply a torque to said drive member in one direction to effect movement of said truing slide from one stop to the other stop of said pair of stops and thereafter to effect pivotal movement of said yoke a predetermined distance away from said positive stop for truing said straight and arcuate portions of said grinding wheel profile, means to reverse said torque to effect movement of said truing slide from the other stop to the one stop of said pair of stops and thereafter to pivot said yoke to engage said positive stop, means to adjust the other stop relative to the one stop of said pair of stops for altering the relationship of said straight and arcuate paths, and means to advance said carriage toward said grinding wheel.
